(57) **CLAIM**

The ornamental design for a diamond segmented tie, as shown and described.

DESCRIPTION

FIG. 1 is a front elevation view of a diamond segmented tie; FIG. 2 is an exploded view of the diamond segmented tie; FIG. 3 is a side elevation view of the diamond segmented tie; and,

FIG. 4 is a back elevation view of the diamond segmented tie.

The broken lines depict probable environment and form no part of the claimed design.

1 Claim, 4 Drawing Sheets
